P. STELLA

GAS LIGHTER

Filed Nov. 3, 1923

Patented June 2, 1925.

1,540,294

UNITED STATES PATENT OFFICE.

PASQUALE STELLA, OF CHICAGO, ILLINOIS, ASSIGNOR OF ONE-HALF TO CHARLES AMICO, OF CHICAGO, ILLINOIS.

GAS LIGHTER.

Application filed November 3, 1923. Serial No. 672,543.

To all whom it may concern:

Be it known that I, PASQUALE STELLA, a citizen of the United States, residing at Chicago, in the county of Cook and State of Illinois, have invented certain new and useful Improvements in Gas Lighters; and I do hereby declare the following to be a full, clear, and exact description of the invention, such as will enable others skilled in the art to which it appertains to make and use the same.

This invention relates to gas lighters and more particularly to a lighter involving the use of an abrasive and a carbon element adapted to produce a spark upon being shifted while in frictional engagement with the abrasive element and which is adapted to be operated simultaneously with the operation of the valve controlling the supply 20 of gas to the burner.

A further object of the invention is to provide a gas lighter which may be applied to various types of burners, and which includes means for operatively connecting 25 the same to the operating means of the burner valve and for holding the carbon element resiliently and positively in contact with the abrasive element at all times, as well as permitting adjustment of the carbon 30 element as it wears off or is consumed in use, thus compensating for the wear of the carbon element and insuring that the same be exposed and in contact with the abrasive element at all times, thereby positively insuring operation of the lighter.

A still further object of the invention is to provide a gas lighter particularly adapted for burners of the type employing incandescent mantles, and it consists in a 40 novel mounting for the lighter element arranged upon the gas burner tube and operatively connected to a cross bar associated with the control valve of the burner, so that the lighter is operated when the valve is opened 45 to permit the gas to flow to the burner for the purpose of igniting the gas and lighting the burner, and is also operated when the valve is closed to cut off the flow of gas to the burner so that if the valve should by inadvertance not be fully closed and the supply of gas entirely cut off, it will be ignited thus providing an element of safety 50 so that the gas will be prevented from escaping or causing asphyxiation or other 55 damage.

While I have shown the invention as particularly applied to a burner having an inverted gas mantle of the incandescent type, it is to be understood that I do not restrict this application to such a type of burner 60 and that it may be applied to any other suitable form of burner as used for lighting, cooking or heating purposes, or to an upright style of mantle, such as is common in the art, without departing from the spirit 65 and scope of the invention, and therefore, I do not desire to be limited to the exact form or relation of parts shown.

The above and other objects and features of novelty of the invention will appear from 70 the detailed description of invention taken in connection with the accompanying drawings forming a part of this specification.

In the drawings:

Figure 1 is a sectional elevation showing 75 my improved gas lighter applied to a gas lamp of the inverted type, the shade holder of the lamp as well as the shade or globe being partly broken away.

Figure 2 is a horizontal cross-sectional 80 view taken on the section line 2—2 of Figure 1, showing the manner of adjusting the carbon element of the lighter.

Figure 3 is a perspective view of an abrasive element employed in connection with 85 and forming a part of the lighter.

Referring to the drawings in detail, in which like reference characters designate corresponding parts throughout the several views, 4 indicates a gas supply pipe leading 90 to a burner, such as the burner 5, having an incandescent gas mantle 6, shown in the present instance as of the inverted type, as is common in the art. Interposed in the supply pipe is a valve 7 in the form of a 95 turn-plug as shown, and provided with a cross bar 8, to the ends of which pendant flexible connections or chains 9 and 10 having rings at their lower ends, are connected 100 for the purpose of manipulating the valve to open and close the same.

The burner 5 includes a vertical supply tube around which the usual air control means 11 is provided, in order to regulate the volume of air which enters the burner tube to combine with the gas therein, as is common in a Bunsen type of burner. The shade holder is indicated at 12, and is provided with the usual or any preferred means 105 of supporting a shade or globe 13 therein, 110

in such a manner as to envelope the burner 5 and the mantle 6.

A rod 14 is pivotally connected with one 5 arm of the cross bar 8, as indicated at 15, preferably near the chain 9 which is ordinarily operated to close the valve 7 and cut off the supply of gas to the burner. This 10 rod 14 extends downwardly through an aperture guide member or bracket 16 carried by the upper portion of the shade 15 holder 12, and also extends through an opening 17 in the shade holder for vertical reciprocation therein. A spring 18 serves to 20 press against the rod 14, thereby resiliently holding it inwardly under pressure, and as shown, is formed as an extension of the apertured guide member 16, which as previously mentioned is mounted upon the shade holder 12. While the spring may be 25 suitably constructed, it will be noted that in the present instance, the spring 18 is formed as an integral part of the bracket and extends upwardly therefrom to bear on and exert inward pressure on the rod.

25 Mounted vertically upon the burner tube within the shade holder 12, is an abrasive element 19, illustrated in the present instance as a metallic member, such as steel, having a roughened or serrated surface and 30 retained in position by a suitable means such as clamps or bands 20 mounted on the burner tube and securing the abrasive element above and in closed proximity to the mantle or burner end of the tube, as previously described. An ignition element such as a carbon stick 21, is mounted horizontally 35 at the lower end of the rod 14 and extends inwardly therefrom for frictional engagement or contact with the serrated surface 40 of the abrasive element 19, and is retained in such engagement by the spring 18.

45 Preferably, the lower end of the rod 14 is provided with a tube 22 receiving the carbon or ignition element 21 at its open inner end and is backed up by a screw 23 threaded in the tube and serving by its adjustment in engagement with the outer end of the element 21 to feed or move the same forwardly to compensate for wear thereon 50 as well as to keep the inner end of the carbon element projected from the end of the tube and exposed for contact with the abrasive element, as clearly shown in Figures 1 and 2 in the drawing. The abrasive element 55 19, which is shown in detail in Figure 3 of the drawings, may be mounted directly on the burner tube and may be provided with side flanges 24, or a holder 25 60 may be soldered or otherwise secured to the burner tube 25, and provided with flanges 26 at the sides, to retain the abrasive element in position and also to guide the carbon or ignition element in its movements 65 along the abrasive element and prevent it from being displaced at the sides thereof.

By this means, positive contact of the ignition element with the abrasive element at all times, is insured, even though there may be slight wear at the wall of the aperture of the guide member or bracket 16 which 70 controls the movements of the rod 14.

When the device is applied to a gas burner employing an incandescent mantle such as shown at 6, a guard or shield 27 is placed around the burner tube beneath the 75 lighter and above the mantle, so that as the ignition element is moved in frictional contact with the abrasive element during the operation of the lighter, the particles of the ignition element which are disintegrated 80 and drop, will strike the guard and be deflected from over the mantle, thereby preventing mutilation or disintegration of the mantle so that its usefulness for lighting purposes will not be impaired. The guard 85 will prevent the particles from dropping on any burner with which it is used.

In the operation of the device, when it is desired to turn on the gas and ignite the same in connection with any burner or lamp, such as described, the operator grasps the chain 10 or suitable ring provided at the lower end thereof and pulls downwardly thereon, thus turning and opening the valve 7 in the supply pipe and at the same time turning the bar 8. The gas will then flow through the burner and the rod 14 by reason of its connection with the other arm of the bar 8, will be shifted vertically, or moved upwardly to cause the ignition or carbon element 21 to scrape or move into frictional engagement with and along the serrated surface of the abrasive element 19. This will produce a spark or sparks which will 95 ignite the gas issuing from the burner tube. When it is desired to extinguish the gas, pull is exerted upon the chain 9 or ring 100 thereof which will close the valve 7 to cut off the supply of gas to the burner, the parts moving from the position shown in full lines in figure to the position shown in dotted lines in said figure. Simultaneously, the ignition element and rod 14, will be moved downwardly owing to the reverse swinging 105 of the bar 8 when the valve 7 is closed, thus moving the ignition element 21 to the lower end of the abrasive element 19. This will cause an additional spark or sparks so that if by any means gas should be escaping, it 110 will be ignited and consumed, thus preventing the gas from escaping in an unconsumed state into a room or rooms and causing explosions or other accidents.

115 It will thus be seen that the invention provides an efficient element of safety in connection with a lighter for burners of any suitable type employing gas or other fuel and that the device is efficient in operation, simple and inexpensive to manufacture, and not likely to get out of working order. By 120 125 130

reason of the guard 27, which may be arranged beneath the lighter, the particles of carbon or other matter which are scraped off when the device is operated, will be prevented from dropping on to the mantle, or burner, when the device is applied to a burner of this type, thus protecting the mantle from disintegration.

While I have shown what I now consider to be the preferred embodiment of the invention, it is understood that I do not desire to restrict myself to the exact form or relation of parts shown, nor the application of the invention to an incandescent gas lamp or burner, but may be applied to gas stoves or other gas burners, and I wish to be protected for such modifications apparent to those skilled in the art as defined by the invention as claimed.

Having thus described my invention, what I claim is:

1. A gas lighter comprising a reciprocating rod, a gas valve, means for reciprocating said rod in conjunction with the operation of the gas valve, an ignition element carried by the rod disposed perpendicular

thereto, an abrasive element secured adjacent the gas discharge, and resilient means engaging the reciprocating rod to force the ignition element into frictional engagement with the abrasive member.

2. A gas lighter as specified in claim 1 in which the abrasive member comprises a channeled body having transverse serrations on its inner bottom face, the side walls adapted to engage and guide the ignition member.

3. In a gas burner having a lever operated valve, a rod pivoted by one end to the valve lever, a tube carried by the rod perpendicular thereto at its other end, an ignition member slidably adjustable in the tube, a channeled member secured to the burner having transverse serrations on its inner bottom face and resilient means engaging the rod adjacent the end with the tube to force the end of the ignition member between the side walls of the channel member and against the serrations.

In testimony whereof I affix my signature.

PASQUALE STELLA.
